United States Patent Office.

JAMES T. HARRIS, OF SWAMPSCOTT, MASSACHUSETTS.

Letters Patent No. 79,070, dated June 23, 1868.

IMPROVED LEATHER-ROLLER.

The Schedule referred to in these Letters Patent and making part of the same.

TO ALL WHOM IT MAY CONCERN:

Be it known that I, JAMES T. HARRIS, of Swampscott, in the county of Essex, and State of Massachusetts, have invented a new and improved Leather-Roller; and I do hereby declare that the following is a full, clear, and exact description thereof, which will enable others skilled in the art to make and use the same, reference being had to the accompanying drawings, forming part of this specification, in which—

Figure 1 is a vertical cross-section of a leather-roller, illustrating my improvement.

Figure 2 is a top view of the same, the rollers being detached.

Figure 3 is a detail cross-section of a modified form of my improved attachment.

Similar letters of reference indicate corresponding parts.

My invention has for its object to furnish an improved attachment for rollers for rolling leather, so as to make the machine more convenient in use, and to do away with the annoyance now so frequently experienced from the wet leather adhering to the roller; and it consists in the guard or guards, in combination with the rollers, as hereinafter more fully described.

A is the frame of the machine, to which the rollers B and C are pivoted, the journals of the lower roller, C, working in slots in the frame A, and being raised, to press the leather with the desired force, by means of a foot-lever, in the ordinary manner.

D is a guard, the ends of which are attached to the frame A, and which is made of such a form as to cover the lower part of that side of the roller B at which the leather passes in between the rollers, its lower edge not extending down so far as to interfere with the said rollers acting properly upon the leather.

E is a guard attached or pivoted to the frame A, so as to cover the upper part of the rear side of the lower roller C. The guard E is made flat, so as to extend back, and serve as a lever to loosen the leather from the roller, should it adhere to it. The guards D and E are so formed that there may be a slot or opening between them, through which the leather passes, as shown in figs. 1 and 3.

If desired, the guards D and E may be made in one piece, or may be rigidly attached to each, as shown in fig. 3; but I prefer to make them separate, as first described, so that they may operate or be used independently of each other. By this construction, as the hand of the operator moves forward with the leather, it will strike against the guards, which are stationary, and be stopped, instead of striking against the revolving roller, and being drawn in between the rollers, and being injured or crushed, and at the same time, should the wet leather adhere to the rollers, by moving the said guard or guards upon their pivoting points, it may be easily detached.

Having thus described my invention, I claim as new, and desire to secure by Letters Patent—

The guards D and E, either or both, and whether made separate or in one piece, in combination with the rollers of a leather-rolling machine, substantially as herein shown and described, and for the purposes set forth.

The above specification of my invention signed by me, this 16th day of March, 1868.
